EARTH MOVING VEHICLE

Ralph L. Beyerstedt, Libertyville, Ill., assignor to
 The Frank G. Hough Co., Libertyville, Ill., a
 corporation of Illinois

Application November 21, 1950, Serial No. 13,074
 Term of patent 7 years

(Cl. D14—3)

To all whom it may concern:

Be it known that I, Ralph L. Beyerstedt, a citizen of the United States, residing at Libertyville, Lake County, State of Illinois, have invented a new, original, and ornamental Design for an Earth Moving Vehicle, of which the following is a specification, reference being had to the accompanying drawing forming a part hereof.

Fig. 1 is a side elevational view of an earth moving vehicle, showing my new design.

Fig. 2 is a front perspective view of the earth moving vehicle; and

Fig. 3 is a rear perspective view of the earth moving vehicle showing a portion of the mechanism raised to an elevated position.

The dominant features of my design reside in the portions illustrated in solid lines.

I claim:

The ornamental design for an earth moving vehicle, as shown and described.

RALPH L. BEYERSTEDT.
